(57) CLAIM

I claim the ornamental design for a cosmetic tool handle, as shown and described.

DESCRIPTION

FIG. 1 is a left perspective view of cosmetic tool handle; FIG. 2 is a left side view of the cosmetic tool handle shown in FIG. 1;

FIG. 3 is a right side view of the cosmetic tool handle shown in FIG. 1;

FIG. 4 is a rear view of the cosmetic tool handle shown in FIG. 1;

FIG. 5 is a front side view of the cosmetic tool handle shown in FIG. 1;

FIG. 6 is a top side view of the cosmetic tool handle shown in FIG. 1; and,

FIG. 7 is a bottom view of the cosmetic tool handle shown in FIG. 1.

Any subject matter shown in dashed lines form no part of the claimed invention.

1 Claim, 4 Drawing Sheets
